Inventor:

GEORGE SCHMIDT,

By John Larrabee
his Attorney.

UNITED STATES PATENT OFFICE

138,603

DESIGN FOR A LINK CHAIN FOR A BRACELET OR THE LIKE

George Schmidt, Los Angeles, Calif.

Application December 1, 1943, Serial No. 111,841

Term of patent 14 years

(Cl. D45—4)

To all whom it may concern:

Be it known that I, George Schmidt, a citizen of the United States, residing at Los Angeles, in the county of Los Angeles and State of California, have invented a new, original, and ornamental Design for a Link Chain for a Bracelet or the like, of which the following is a specification, reference being had to the accompanying drawing, forming a part thereof.

Figure 1 is a plan view of a link chain for a bracelet, or the like, showing my new design.

Fig. 2 is an edge view thereof.

I claim:

The ornamental design for a link chain for a bracelet, or the like, as shown.

GEORGE SCHMIDT.
